UNITED STATES PATENT OFFICE.

JAMES E. MEED, OF PALESTINE, WEST VIRGINIA.

RATCHET BIT-BRACE.

1,356,776.

Specification of Letters Patent. Patented Oct. 26, 1920.

Application filed September 22, 1919. Serial No. 325,381.

To all whom it may concern:

Be it known that I, JAMES E. MEED, a citizen of the United States, residing at Palestine, in the county of Wirt and State 5 of West Virginia, have invented new and useful Improvements in Ratchet Bit-Braces, of which the following is a specification.

This invention relates to ratchet bit braces, and one object of the invention is to 10 provide a simple, reliable, efficient and durable type of ratchet mechanism readily adjustable for rotating the tool carrying member to the right or left or rigidly fixing said tool carrying member to the driving 15 crank.

A further object of the invention is to provide a ratchet mechanism and construction of tool supporting head forming a casing therefor which admits of the convenient 20 assembly of the parts and their disassembly for cleaning, repairs or renewal of worn or defective parts.

A still further object of the invention is to provide a clutch mechanism which is 25 positive in action and in which the pawls and ratchet wheel are adapted to afford long service before their renewal is required.

A still further object of the invention is 30 to provide a driving crank which is adjustable to vary its effective radius or leverage as occasion may require.

A still further object of the invention is 35 to provide means for properly locking and centering the parts of the adjustable crank.

With these and other objects in view, the 40 invention consists of the features of construction, combination and arrangement of parts, hereinafter fully described and claimed, reference being had to the accompanying drawing, in which:—

Figure 1 is a side elevation of a ratchet bit brace embodying my invention, with parts in section and parts of the tool carrying member omitted.

Fig. 2 is a sectional plan view of the tool carrying head and casing and parts of the ratchet mechanism.

Fig. 3 is a plan view of one of the sliding pawls.

Fig. 4 is a cross-section on line 4—4 of Fig. 1 on an enlarged scale.

In carrying my invention into practice I provide an oscillatory or rotary tool carrier 55 1. This may be of any preferred form

and construction, and provided with any preferred type of adjustable jaws. In practice, the tool carrying member, the frame only of which is shown, may be provided with suitable guides to receive jaws which are adapted to expand under spring pressure and are threaded for engagement with an adjusting sleeve, whereby they may be moved inwardly and outwardly, the grooves in the frame member permitting the jaws 60 to spread on their outward movement and causing them to contract or move together on their inward movement. I have not shown the specific construction of the jaws and their adjusting means, as they may be 65 of any conventional type and constitute no part of the present invention.

The tool carrying member 1 includes a shaft 2 supported by a right-angled tool carrier head and ratchet mechanism casing 75 3. This head or casing 3 preferably consists of a casing having a vertical arm 4 and a horizontal arm 5. The outer end of the horizontal arm 5 is bifurcated to form a chamber 6 and the arm 4 is connected with the lower wall of this chamber and provided with a bore 7 in which the shaft 2 is journaled, while the upper wall of the bifurcation is formed with an opening 8 receiving the upper end of a reduced stem 9 85 integral with the shaft 2, said stem being provided with a threaded socket to receive a retaining screw 10, whereby the parts named are detachably held in properly related position. A sleeve or collar 11 surrounds the shaft 2 and abuts against a removable washer 11' disposed between said sleeve and the base of the arm 4, said sleeve being secured in position by a set screw or other suitable fastening 12. This sleeve 90 95 assists in holding the tool carrier from upward movement and may also form a stop to hold in position, the internally threaded rotary adjusting sleeve (not shown) through the action of the threads of which 100 the jaws of the tool are adjusted, as is common in devices of this character. The washer 11' sustains the wear and reduces the friction between the working parts described and being removable, may be detached when worn and another substituted in its place, with resultant economy.

The horizontal arm 5 of the head 3 may form an integral part of the lower arm 13 of a driving crank of generally ordinary 110

form but of novel construction, said crank embodying the lower arm 13, above referred to, an upper arm 14 and a handle 15, the arm 14 carrying the usual swiveled head 16 and the handle 15 the usual rotary grip 17. These parts are constructed and combined in a novel manner so that the length of the crank and its radius or leverage may be varied, as will be fully hereinafter described.

The chamber 6 has arranged therein a ratchet wheel 18 which surrounds the stem 9 and is fixed thereto by a set screw or other suitable fastening 19, said wheel 18 being provided around its periphery with ratchet teeth or recesses 20. One side of the chamber 6 may be closed by a wall 21 integral with the head 3, while the opposite side is provided with a removable closure 22 which may be suitably secured in position, as indicated at 23 and 24, in any manner to permit of its removal or adjustment to open and closed positions to admit of the ready and convenient application and removal of the ratchet wheel. The ratchet wheel is adapted for co-operation with a pair of superposed pawls 25 and 26 arranged in a chamber 27 formed in the arm 5, which chamber communicates through a guide slot 28 in the chamber 6. Each of these pawls 25 and 26 is of generally similar construction, comprising a generally rectangular or oblong rectangular block or plate provided at its forward end with a reduced tooth beveled on one side, the dog 25 having the tooth 25' beveled on its right hand side, which teeth project through the slot 28 for co-operation with the teeth of the ratchet wheel. A web 29 projects from the arm 3 forwardly into the chamber 27 and subdivides the same into upper and lower pawl receiving spaces, said web forming a guide which spaces the pawls from each other but maintains them in proper relationship. Projecting rearwardly from each pawl is a stud or pin 30 removable in a guide recess or socket 31 in the arm 13 and surrounded by a coiled spring 32. The pawls 25 and 26 are slidably mounted for backward and forward adjustment into and out of engagement with the ratchet wheel and are adapted to move forward by the springs and to recede against the resistance of said springs.

Surrounding the arm 5 is a rotary and sliding pawl controller 33, designed to change the direction of movement of the ratchet mechanism from clock-wise to anti-clock-wise or vice versa when so operated, the same comprising a ring or sleeve limited in its forward movement by a stop shoulder 34 and having a limited degree of rearward sliding movement governed by a stop shoulder 35 adapted to engage the rear wall of the chamber 27. The pawls 25 and 26 are respectively provided in their upper and

lower edges with grooves 36, and the controller ring or sleeve 33 is provided with an internal spiral rib 37 engageable with said grooves whereby the two pawls may be simultaneously released for a locking action, as hereinafter described, or may be simultaneously and alternately adjusted into and out of ratchet wheel engaging position. The spiral rib extends partially around the controller ring, to a degree somewhat less than one-half the circumference of said ring, so that when the ring is in normal or neutral position the ring will be out of engagement with the grooves 36, allowing both pawls 25 and 26 to be moved forward by their springs into ratchet wheel engaging position, as shown in Fig. 1. On the other hand by rotating the ring a certain degree from a neutral position in one direction, the rib will engage the groove 36 of one pawl, and such pawl will be retracted or moved rearwardly leaving the other pawl free for action, while on rotating the ring to a like degree in the opposite direction, the reverse action with relation to the pawls will occur. Hence when the ring is turned from a neutral position to the right, the dog 25 for instance, will be retracted or moved rearwardly to an inoperative position and locked in such position to the ring 33, while the dog 26 will be left free for the ratchet action, and on the contrary when the ring is turned to the left or in the opposite direction, the dog 26 will be retracted and the dog 25 left free for a ratchet action, as will be readily understood. It will therefore be seen that when either dog is free for operation it will be permitted to be moved forward by its spring to engage a tooth in the ratchet wheel and to slide rearwardly by pressure on its beveled face for disengagement from said tooth and for subsequent movement into engagement with the next tooth of the ratchet wheel, while the other pawl or dog remains idle and locked in retracted position to the ring.

Mounted upon the arm 13 is a locking and releasing sleeve 38 having a threaded connection with said arm, as indicated at 39, said sleeve being limited in its forward movement on the arm by a stop flange or shoulder 40. When the dogs are free from engagement with the rib 37 it will be understood that both dogs will be projected by their springs into engagement with the ratchet wheel, thus locking the ratchet wheel against movement in either direction, whereby the tool carrying member 1 will be fixed to the driving crank for rotation so as to make the connection absolutely rigid and prevent play of the parts or lost motion when the ratchet mechanism is not in use for a ratchet action. When it is desired to fixedly couple the tool carrying member to the driving crank, the sleeve 38

is adjusted, if not already adjusted, to release both pawls to permit them to be moved into engagement with the ratchet wheel by their springs 32 and the sleeve 38 is then 5 rotated forwardly until it engages the flange 40. Said sleeve 38 will thus be brought to bear at its forward edge against the rear edges of the dogs 25 and 26, thus locking the dogs in rigid engagement with the 10 ratchet wheel so that no play or lost motion can occur in a direct driving action. When the sleeve 38 is turned backwardly or retracted, both dogs will be freed for sliding movement and the sleeve 33 will also be 15 freed for adjustment to throw either dog into action and hold the other retracted. Accordingly it will be understood that through adjustment of the sleeve 33, when the sleeve 38 is retracted, either dog may be 20 adjusted to coöperate with the ratchet wheel for turning the tool carrying member to the right or left on the oscillation of the driving crank.

It will be evident from the foregoing description that as the ratchet wheel 18 is disconnectible from the tool carrying member, the wheel may be removed and a new one substituted in its place whenever the teeth thereof become worn to a degree requiring 30 its replacement, but that, owing to the form and size of the ratchet wheel, teeth or recesses affording a large extent of rear surface may be provided so that the ratchet wheel will last a long period and will require replacement only at very long intervals. It will be observed that the dogs are arranged in vertical alinement with each other, and in longitudinal alinement with the axis of the wheel and the crank driving 40 arms, thus insuring certainty of operation in the ratchet driving action, as well as the firm and positive rigid engagement between the dogs and ratchet wheel when said dogs and ratchet wheel are rigidly locked together. A type of ratchet mechanism is thus provided which is more positive and certain in action and is subject to less wear and tear than ratchet devices which engage the ratchet wheel, off center, thus increasing 45 the efficiency and durability of the tool. It is also evident that in the use of the sleeve 38 as when the same is moved into contact with the pawls 25 and 26, a rigid connection is established between the parts of the brace 50 such as approximates that of the ordinary type of brace from which the ratchet is eliminated. This sleeve is preferably to be used for the purpose, as described, only when the ratchet mechanism is not to be 55 brought into play for a relatively long period of time, so as to eliminate any possible or undue wear and tear on, or displacement of, the pawls and springs, as might otherwise occur, particularly, after long and 60 hard usage of the device. The sleeve 38 is

only operable in the manner aforesaid, when the sleeve 33 is entirely free from engagement with the pawls 25 and 26.

The arms 13 and 14 are hollow to form tubular portions which telescopically receive 70 arms 13' and 14' integral with the handle 15, thus enabling the handle to be adjusted to regulate the length of the driving crank and consequently its swing or radius of action and its driving leverage. Each arm 75 13' and 14' is provided with a series of locking recesses 41 for locking engagement with a spring actuated detent 42 on the arm 13 or 14, as the case may be, to lock the parts against longitudinal movement. The recesses 41 may be set at certain distances apart to permit of accurate predetermined 80 adjustments. Each arm 13' and 14' is also provided with means for holding it against rotation in the tubular portion of the arm 85 13 or 14 engaged thereby, such means shown in the present instance consisting of one or more ribs 43 thereon engaging a longitudinal groove or grooves 44 in the tubular portion of the arm 13 or 14 in which it fits. 90 These ribs and grooves also provide a means for indicating positively the positions in which the parts 13' should be inserted in order to bring the recesses 41 into alinement with the detents 42 for a locking action, and 95 to insure proper seating of the arms 13 and 14 in vertical alinement with each other. Each arm 13 and 14 is preferably provided with a beveled end portion 45, which is longitudinally slit, as indicated at 46, dividing 100 it into a plurality of spring fingers adapted for wedging engagement with the arms 13' and 14'. At their inner extremities each beveled end is externally threaded to receive the internally threaded inner end of a 105 clamping collar or sleeve 47, which is internally beveled for an obvious purpose. The tapered end of each arm may be formed with annular grooves 48 to diminish the amount of the surface engaged by the bevelled sleeve and thus diminish friction, allowing the bevelled sleeve to be easily and conveniently adjusted for a clamping or releasing action. By the described construction a firm locking engagement between the 110 telescopic parts of the upper and lower crank driving arms and the driving crank is insured to render the crank rigid when the parts are assembled.

Having thus fully described my invention, 120 I claim:—

1. In a ratchet bit brace, a tool carrying member, a driving crank, a ratchet wheel carried by the tool carrying member, a pair of spring actuated reversely acting dogs to 125 engage the ratchet wheel, a rotary and sliding ring having means for simultaneously engaging and projecting one dog and retracting the other or for freeing both dogs for wheel engaging movement, and means 130

for locking the freed dogs rigidly in engagement with the ratchet wheel.

2. In a ratchet bit brace, a tool carrying member, a driving crank, a ratchet wheel on the tool carrying member, a pair of spring actuated reversely acting dogs to engage the ratchet wheel, a rotary and sliding ring having means for simultaneously engaging and projecting one dog and retracting the other or for freeing both dogs for wheel engaging movement, and a rotary locking sleeve adjustable to release the dogs and ring for individual action or to lock the dogs and ring rigidly from movement in wheel engaging position.

3. In a ratchet bit brace, the combination of a tool carrying member, a driving crank, a ratchet wheel on the tool carrying member, a pair of spring actuated reversely acting dogs to engage the ratchet wheel, a device for simultaneously engaging and pro-

jecting one dog and retracting the other or for freeing both dogs for wheel engaging movement, and means for locking the freed dogs rigidly in engagement with the ratchet wheel.

4. In a ratchet bit brace, a tool carrying member, a driving crank, a ratchet wheel on the tool carrying member, a pair of superposed longitudinally sliding, reversely acting spring actuated dogs to engage the ratchet wheel, a rotary and sliding ring having a cam engagement with the dogs for simultaneously projecting one and retracting the other or freeing both dogs for wheel engaging movement, and a rotary locking sleeve on the crank adjustable to release the dogs and ring for individual action or to lock the dogs and ring rigidly from movement in wheel engaging position.

In testimony whereof I affix my signature.

JAMES E. MEED.
